DESIGN FOR A DANGER SIGNAL

Harold W. Faunce, Ventnor, N. J.

Application May 25, 1937, Serial No. 69,535

Term of patent 14 years

To all whom it may concern:

Be it known that I, Harold W. Faunce, a citizen of the United States of America, residing at Ventnor city, in the county of Atlantic and State of New Jersey, have invented a new, original, and ornamental Design for Danger Signals, of which the following is a specification, reference being had to the accompanying drawing, forming part thereof.

Fig. 1 is a front elevation of a danger signal showing my new design.

Fig. 2 is a side elevation thereof with the support arm fragmentarily shown for convenience of illustration.

I claim:

The ornamental design for a danger signal as shown and described.

HAROLD W. FAUNCE.
